UNITED STATES PATENT OFFICE.

JOHN G. CALLAN, OF NAHANT, AND WERNER JOHNSON, OF LYNN, MASSACHUSETTS,
ASSIGNORS TO GENERAL ELECTRIC COMPANY, A CORPORATION OF NEW YORK.

COMBINED EMERGENCY AND THROTTLE VALVE.

No. 927,943.

Specification of Letters Patent.

Patented July 13, 1909.

Application filed February 27, 1908. Serial No. 418,039.

To all whom it may concern:

Be it known that we, JOHN G. CALLAN and WERNER JOHNSON, citizens of the United States, residing at Nahant and Lynn, respectively, county of Essex, State of Massachusetts, have invented certain new and useful Improvements in Combined Emergency and Throttle Valves, of which the following is a specification.

10 The present invention relates to valves for starting and stopping steam engines which are so constructed and arranged that they may be opened and closed slowly for normal operation, and closed suddenly when for any reason it becomes necessary or desirable.

15 The object of our invention is to provide a valve of the above mentioned character, which is simple and rugged in construction and reliable in operation and requires a minimum amount of attention to keep it in working condition.

20 In the accompanying drawings, which illustrate one of the embodiments of the invention, Figure 1 is a partial view in end elevation of a steam turbine fitted with our improved valve; Fig. 2 is an axial section of the valve; Fig. 3 is a detail view partly in cross-section, showing the arrangement of the hooks for supporting the weight; and Fig. 4 is an enlarged detail view of the upper 25 end of the valve-stem, showing the latch and other parts for holding the nut on the valve-stem.

25 1 indicates the casing of the turbine which may be of any desirable construction and 2 is the main shaft therefor. The turbine is controlled by a speed governor 3 driven by the low-speed shaft 4 from the main shaft through speed-reducing gearing.

30 5 indicates the casing of the valve mechanism and 6 the chest by which steam is admitted to the turbine from the combined emergency and throttle valve 7. This valve is arranged to be opened and closed under normal conditions by the hand-wheel 8, and is closed under emergency conditions by the weight 9. The weight is normally held in the position shown by the hooks 10 which are mounted upon the horizontal rock-shaft 11. Mounted on the rock-shaft 11 is an arm 12 having a counterweight 13, which tends at all times to move the hooks in a manner to release the weight. Attached to the lower end of the arm 12 is a connecting rod 14, the

lower end of which is connected to a lever 15 having a pivot 16. The rod 14 is kept under tension by the counterweight 13. Also mounted on pivot 16 is an arm 17 which normally engages a stop trigger 18, suitably pivoted at one side of the main shaft. This trigger holds the counterweight under normal conditions and prevents it from releasing the main weight.

35 Mounted upon a disk or other support driven by the main shaft are two clock-springs 19, each of which forms an emergency governor for actuating the trigger 18 when the speed becomes abnormally great. The inner end of each spring is fastened to a support, while the outer end is free, and when the centrifugal force exceeds a predetermined amount, due to abnormal speed conditions, the said free end moves outward and strikes the trigger, which releases the parts 17, 15, 14, 12, 13 and 10, and permits 40 the main weight 9 to fall and close the valve suddenly. The emergency weight is reset by hand after the valve is closed and the turbine stopped, as will appear hereinafter, as will also the opening of the valve.

45 Referring more particularly to Figs. 2 to 4, inclusive, 25 indicates the casing of the valve, having suitable flanges for connecting it to the steam-chest and also to the supply-main and a horizontally extending partition that divides the interior thereof. This partition is bored centrally and afterward screw-threaded to receive the removable valve seat 26. Mounted on top of the casing is a bonnet 27 through which the valve-stem 28 passes. Leakage of fluid around the stem is prevented by the packing and gland 29. The under side of the valve casing is also provided with a bonnet 30 containing a packing and gland 31 to prevent the escape of 50 fluid around the lower portion of the valve-stem. The stem may with advantage be made of steel, and surrounding it above and below the valve are sleeves 32 made of some non-rusting material, the object of this being to prevent the parts from sticking due to rust. Mounted on the gland of the lower packing is a receptacle or cup 33 that is piped to any convenient point for carrying off any water which may collect therein. 55 The valve-stem is made in two principal parts, the lower part being provided with a piston 34 which fits into suitable guides ter-

minating at their lower end in an annular space that forms the cylinder part of a dash-pot. Situated above the piston are radial guides 35 that engage and are guided by the bore of the valve seat. The upper end of this portion of the valve-stem is provided with a screw-thread 36 and a slotted head 37. On said threaded portion is screwed a removable valve 38 which is provided with suitable spanner-holes or notches to receive a wrench used in setting up or removing the valve. The slotted portion 37 of the lower part of the stem is arranged to receive the enlargement on the lower end of the upper part of the stem and is so shaped that both parts of the stem move longitudinally at all times as a unit, while the upper part can be rotated independently of the lower part. Mounted on top of the upper bonnet is a frame 39 having an annular base portion and a tubular upper portion that is suitably finished on the outside to form a guide for the main weight and is finished internally to receive the sliding nut 40 screw-threaded to the valve-stem. The nut 40, prevented by a spline from turning, is normally held in the raised or operative position shown by the latch 41, Fig. 4, which is carried by the spindle or pivot 11. This latch engages a lip formed on the part 42, which is secured to the nut by a screw or other means. We prefer to make the part 42 separate from the nut so that the surfaces engaging the latch 41 can be hardened to prevent wear, but this is not always necessary. Mounted on the valve-stem 28 is a collar 43 which by engaging the part 42 acts as a stop to prevent the valve from being moved upward to a position within the casing where it will jam and prevent or tend to prevent the valve from operating under emergency conditions. Mounted on the upper end of the valve-stem is a hand-wheel 8 of any suitable construction. This hand-wheel is keyed to the stem and at all times moves therewith. Under normal conditions the valve may be opened and closed by rotating the hand-wheel in one direction or the other just the same as with an ordinary screw-valve. When, however, it is desired for any reason to close the valve suddenly, latch 41 is withdrawn from engagement with the nut 40, and after these parts are disengaged hooks 10 are moved far enough to the right (Fig. 1) to release the pins 45 attached to the main weight 9, and the latter is permitted to fall. As soon as the weight is released it drops and the internal shoulder 46 strikes the collar 47, mounted on the valve stem with a hammer-blow, due to the lost-motion, and suddenly starts the valve into motion. The collar 47 is held against axial movement by the shoulder on the stem below it and the collar above. The ends of the collar project 65 through the side slots in the tubular central

guide or member, and are sufficiently near the walls of the slots to prevent the stem from buckling from any cause. The valve moves more rapidly at the upper end of its stroke than at the lower, because it is un-checked at the start, while the dash-pot formed by the piston 34 and the cylinder space in the lower part of the valve casing cushions its seating. This arrangement is advantageous because under these conditions 75 it is desirable to close the valve as quickly as possible without, however, injuring the seat.

The action of our improved valve is as follows: Assuming that the speed of the 80 turbine-shaft exceeds the normal by any pre-determined amount, as, for example, 10 or 15 per cent., the free ends of the clock springs reach outward and strike the end shown in dotted lines of the trigger 18. 85 This releases the arm 17, lever 15 and the counter-weight 13 swings the latch 41 and hooks 10 to the right. The latch 41 is so adjusted with respect to the hooks 10 that hold the weight that it disengages the nut 90 before the hooks 10 release the weight. As soon as the weight falls it imparts a hammer-blow to the valve and closes it. Assuming the valve to be closed after an emergency operation and that it is desired to reset the 95 same, the hand-wheel 8 is rotated to the right, (the closing movement under normal conditions). Since the valve is seated and the stem 28 is prevented from moving downward, it follows that the rotation of the 100 hand wheel and stem as specified will cause the nut 40 to move upward on the stem until it strikes the projection or shoulder 49 on the frame 39; the said shoulder acting as a stop to prevent further movement. The 105 next step is to move the weight 9 up into the position shown in the figures by hand and cause the hooks 10 to engage the pins 45. It will be observed that the hooks are provided with flat inclined surfaces or cams 110 52 so that as the weight is moved upward to about its normal position they will be struck by the pins 45 on the weight and forcibly swing the lower parts of the hooks under the pins and about the rock-shaft 11 115 as a center. This action also moves the latch 41 into place, and through the rod 14 the part 17 of the emergency governing mechanism is moved to its normal position. The weight is then lowered slightly until it 120 rests on the hooks. The trigger 18 is so arranged that it will automatically return to place and lock the parts when the hook 10, latch 41, rod 14 and arm 17 are reset or returned to their normal positions. This 125 action may be brought about by any suitable means, as for example by making the left-hand end of the trigger slightly heavier than the other end. This arrangement is particularly desirable since the attendant can 130

use both hands to reset the weight and at the same time avoid having to set the hooks by a separate operation. The third and last step in the operation consists in turning 5 the hand-wheel to the left, (the direction opposite to that required to reset the nut), and the valve will open the same as any ordinary throttle valve of the nut and screw type. If it be desired to shut down the 10 turbine by hand, it is only necessary to rotate the hand-wheel in a direction to close the valve, all the other parts remaining in the position shown in the drawings.

In order to simplify and cheapen the valve, 15 the weight 9 is cast in one piece with slots 50 arranged diametrically opposite, which very greatly weaken the metal at these points. After the weight is bored and the central portion of its periphery finished, it is broken 20 in halves in line with the slots. The weight can then be mounted in place around the guide carried by the upper valve bonnet, after which a ring or band 51 is shrunk on the outside. The adjacent surfaces of the 25 fracture will be sufficiently rough to prevent one part from moving independently of the other.

Care should be exercised to see that the latch lets go of the nut before the hooks 30 release the weight, since otherwise the weight would be unable to close the valve, or if the impact was sufficient to move the latch slightly it might injure the same.

Our improved valve possesses many advantages in the way of simplicity and decreased cost of construction. It is very compact and the parts are all simple and rugged in character and of a kind not liable to get out of order. By using a tubular guide 40 it can be very readily machined and by mounting it centrally with the nut inside and the weight outside, one guide serves for two purposes; and since the guide can be rigidly bolted to the casing, there is no danger of the 45 parts getting out of line. By making the lower end of the stem larger than the upper, it has a self-closing tendency, which is helpful in closing the valve, particularly under emergency conditions. Owing to the construction and arrangement of the parts, the 50 valve may be freely opened and closed by hand, without regard to the emergency tripping mechanism, and the latter will operate the valve suddenly, even though the engineer 55 be in the act of closing or opening the valve by the hand-wheel.

The valve may be closed manually through the medium of the weight by raising the arm 12, which is connected to the latch 41, and the 60 hooks 10, although this ordinarily would not be found desirable, because it necessitates the resetting of the parts.

It is preferable, but not essential, in all cases that the valve shall have a self-closing 65 tendency. This will depend largely upon the

conditions under which the valve is to be used.

In accordance with the provisions of the patent statutes, we have described the principle of operation of our invention, together 70 with the apparatus which we now consider to represent the best embodiment thereof; but we desire to have it understood that the apparatus shown is only illustrative, and that the invention can be carried out by other 75 means.

What we claim as new, and desire to secure by Letters Patent of the United States, is,—

1. In combination, a valve, a casing therefor, a screw-threaded stem for the valve, 80 a sliding nut, a handle for the stem, a central member within which the nut is guided, a means for supporting the nut, a weight that surrounds the member and is guided thereby, and a device for releasing said means. 85

2. In combination, a valve having a self-closing tendency, a casing therefor, a screw-threaded stem and nut for normally opening and closing the valve, a handle for the stem, a central member that guides the nut after 90 it is released, a means carried by said member which engages and normally supports the nut, a device for releasing the means and permitting the valve to close, and a weight which surrounds and is guided by said member for assisting the valve to close. 95

3. In combination, a valve having a self-closing tendency, a casing therefor, a screw-threaded stem and nut for normally opening and closing the valve, a handle for the 100 stem, a central member that guides the nut after it is released, a hook carried by said member which directly engages and normally supports the nut, a device for releasing the hook and permitting the valve to 105 close, and a weight which assists in closing the valve and is guided in its descent by said member.

4. In combination, a valve, a threaded stem and sliding nut for opening and closing 110 the valve under normal conditions, a latch that supports the nut, a suspended weight which closes the valve when it falls, and a means which first withdraws the latch and thereafter releases the weight. 115

5. In combination, a valve, a threaded stem and sliding nut for opening and closing the valve under normal conditions, a latch that supports the nut, a suspended weight which closes the valve when it falls, 120 a hook for sustaining the weight, and a means which first withdraws the latch and thereafter the said hook.

6. In combination, a valve having a self-closing tendency, a threaded stem therefor, 125 an actuator for the stem, a sliding nut through which the stem extends, a stop which engages the nut and limits its movement in one direction, a handle for actuating the valve through its stem, a device for re- 130

taining the nut in its normal position, and means for releasing the device and permitting the valve to close.

7. In combination, a valve, a casing therefor, a screw-threaded stem for the valve, an actuator for the stem a sliding nut through which the stem passes, a tubular guide mounted on the casing within which the nut slides, a weight which surrounds the guide and whose movements are directed thereby, and means which normally support both the nut and the weight and release them one after the other in closing the valve.

8. In combination, a valve, a casing therefor, a screw-threaded stem for the valve, a sliding nut through which the stem passes, a handle for the stem, a central guiding member mounted on the casing within which the nut slides, a stop to limit the travel of the nut in one direction, a stop on the stem for limiting its travel in one direction, a latch for supporting the nut, and a means for releasing the latch when it is desired to close the valve suddenly.

9. In combination, a valve, a casing therefor, a screw-threaded stem for the valve, a sliding nut through which the stem passes, a tubular guide mounted on the casing within which the nut slides, a stop in the bore of the guide to limit the travel of the nut, a stop on the stem for limiting its movement within the nut, a weight which surrounds the guide and whose movements are directed thereby, a latch for supporting the nut, a hook for supporting the weight, and a connection between the latch and hook which insures the former acting before the latter.

10. In combination, a valve, a casing therefor, bonnets closing the ends thereof, a tubular member mounted on one of the bonnets, a threaded stem which extends through both bonnets and into the bore of said member, one portion of the stem being larger than the other to give the valve a self-closing tendency, a nut mounted on the stem and arranged to slide without turning in the said member, a pivoted latch carried by the member which normally directly engages and sustains the nut, and a means for releasing the latch.

11. In combination, a valve, a screw-threaded stem, a sliding nut which engages the stem, a collar on the stem, a suspended weight which when it falls strikes the collar and closes the valve, a latch for sustaining

the nut in its normal position, a means for sustaining the weight, and a connection for operating the latch and means successively.

12. In combination, a valve, a screw-threaded stem, a sliding nut which engages the stem, a tubular guiding member for the nut, a suspended weight that is also guided by the member, a collar on the stem which projects through the walls of the member and is guided thereby to prevent the stem from buckling and which is struck by the falling weight, a latch for normally sustaining the nut, a means for normally sustaining the weight, and a mechanism for releasing the latch and means.

13. In combination, a valve, a casing therefor, a stem for the valve, packings around the stem where it projects through the casing, non-rusting sleeves which inclose the stem and slide in the packings, and means for operating the valve.

14. In combination, a valve, a screw-threaded stem, handle and sliding nut for opening and closing the valve under normal conditions, a latch that supports the nut and through it the valve when the latter is moved by the stem and handle, a motor for closing the valve suddenly when released, a means for restraining the motor from acting, and emergency mechanism which first moves the latch in a direction to release the nut and thereafter moves said means in a direction to release the motor.

15. In combination, a support, a weight, a device carried by the support for sustaining the weight, a means actuated by the weight as it is raised for moving the device into a position to receive and sustain said weight, and an agent which is actuated by the weight as it falls.

16. In combination, a support, a weight, a hook carried by the support for sustaining the weight, a means carried by the hook and actuated by the weight as it is lifted for moving the hook into a position to receive and sustain the weight when it is slightly lowered, and an agent which is actuated by the falling weight.

In witness whereof, we have hereunto set our hands this 24th day of February, 1908. 105

JOHN G. CALLAN.
WERNER JOHNSON.
